UNITED STATES PATENT OFFICE.

WILLIAM H. RABBE, EDWARD W. HARDEN, AND MICHAEL E. DEMPSEY,
OF HAMILTON, OHIO.

SPRING RAIL-FROG.

SPECIFICATION forming part of Letters Patent No. 729,661, dated June 2, 1903.

Application filed October 27, 1902. Serial No. 129,033. (No model.)

To all whom it may concern:

Be it known that we, WILLIAM H. RABBE, EDWARD W. HARDEN, and MICHAEL E. DEMPSEY, citizens of the United States, residing at Hamilton, in the county of Butler and State of Ohio, have jointly invented certain new and useful Improvements in Spring Rail-Frogs, of which the following is a specification.

10 It is the object of our invention to provide a new and improved spring rail-frog in which the spring-pressed movable wing-rail rocks on a vertical pivot located in rear of the meeting points of the point-rails of the main track and siding, while the free end of the movable rail takes into the gap between the ending of the point-rails and the continuation of the main rail and is normally held therein by spring-pressure, thereby assuring ease of operation and preventing loosening of bolts and torsion of parts.

15 Another object of our improved device is to rock the movable wing-rail on a vertical pivot located outside the main and siding rails in rear of the points and to provide the free end of the movable wing-rail with a reinforce-rail lapping the adjacent ends of the movable wing-rail and continuation of the main rail and acting as a riser-rail to protect the meeting ends of those rails from jar.

20 Another object of our improved device is to provide the movable wing-rail with a diagonally cut end face and to give the movable wing-rail its greatest movement at that diagonally cut end face, while the movable wing-rail at its point of greatest movement forms a part of the main track parallel with the main-track rail.

25 This construction provides a spring rail-frog which is compact and cheap in construction, instantly responsive to side pressure from wheels passing along the siding without torsion of parts, returning instantly and positively to normal position immediately that the

30 wheels have passed the movable wing-rail along the siding, insuring the normal retention of the gap-filling part of the movable wing-rail in line with the main rail, and minimizing wear of the operating parts.

35 Our invention consists in the parts and in the construction, arrangement, and combina-

tions of parts hereinafter more fully described and claimed, and the same will be readily understood from the following description and claims, and from the drawings, in which 55 latter—

Figure 1 is a plan view of our improved device. Fig. 2 is a cross-section taken on the line $x-x$ of Fig. 1, showing the manner of applying the spring. Fig. 3 is an end elevation, partly in section, on the line $z-z$ of Fig. 1, showing the manner of pivoting the movable wing-rail. Fig. 4 is a cross-section taken on the line $y-y$ of Fig. 1, showing the means at the free end of the movable wing-rail for preventing tilting of that rail; and Fig. 5 is a plain view of the reinforce-bar for the movable wing-rail.

A A' represent the main rails, and B B' the rails of the siding.

C represents the point of the main rail, and D the point of the siding.

The main rail A' ends in a diagonal cut F in the longitudinal plane of the main rail in advance of the point-rails, thereby forming 75 the gap G, which is filled by the free end h of the movable wing-rail H. The movable wing-rail has a diagonal cut h to mate the diagonal cut F. The free or swinging end h of the movable wing-rail extends in a plane 80 longitudinal of the main rail, and the movable wing-rail is bent backwardly at i and projected to a point in rear of the points C D, as shown at I, the inner face i' of the extension I hugging the diagonal face c of the 85 point C. The movable wing-rail is pivoted at its heel or rear end by having an upturned and inwardly-projecting bracket k fastened to the track-plate 1. A U-shaped spanner k' takes to both sides of the inwardly-projected end k^2 of the bracket k . A reinforce-bar L is fastened to the outer side of the web of the movable wing-rail. A bolt k^3 , having a squared head k^4 , takes through the spanner-plate k' , reinforce-bar L, and the movable 95 wing-rail and is securely fastened therein by the nut k^5 , a pivot-pin k^6 taking through the apertures in the spanner-plate and bracket for pivotally securing the movable wing-rail to the plate 1. As seen in the drawings, the inwardly-projecting end k^2 of the bracket and the spanner-plate k' considerably over-

lap each other for preventing a tilting of the movable wing-rail out of its vertical position at its pivoted end and at the same time insure an easy turning of the rail on its pivot.

- 5 A reinforce-rail M is properly secured to the free end of the movable wing-rail, having a portion m overlapping the main rail A' for preventing the movable wing-rail being projected inwardly beyond its proper limit for 70
 10 alinement with the main rail. It also has a portion m' bent outwardly and extending longitudinally of the bent portion I of the movable wing-rail II. The portion m^2 of the reinforce-rail M between the bent portion m' 75
 15 and the overlapping portion m lies parallel with the portion h of the wing-rail H and laps the diagonal cuts of the movable wing-rail and continuation of the main rail. The reinforce-rail is secured to the movable wing- 80
 20 rail by bolts, with filling-blocks 23 between the rails. The reinforce-bar L extends longitudinally of the movable wing-rail and is bent over upon itself, as shown at l, for forming a filling-in block between the movable 85
 25 wing-rail and reinforce-rail.

The rails A B A' B' are rigidly secured together for forming a compact body to prevent relative creeping of the rails. Thus a filling-in block 4 is securely bolted to and between the tracks A B. A filling-in block 5 is secured to and between the tracks A' B', and a filling-in block 6 is bolted to and secured between the point-rails and the rigid wing-rail, the whole being secured to the 90
 30 plates 17. Stops 8 limit sidewise displacement of the movable wing-rail.

The movable wing-rail is provided with a depression h^2 , and the outer end of the reinforce-rail secured thereto is provided with an inclined face m^3 for receiving the outer edge of the tread of the wheel, which in practice is usually of greater diameter than the tread adjacent to the wheel-flange owing to the wear, the reinforce-rail therefore also acting 95
 40 as a riser-rail and protecting the adjacent diagonal ends of the movable wing-rail and continuation of the main rail. The rail B' is bent at b for projecting longitudinally of the main rail, but separated therefrom by the 100
 45 filling-in block 6 and having a second outward bent b' for forming a rigid wing-rail for the main rail. The longitudinal portion h of the movable wing-rail is normally projected 105
 50 to fill the gap by having the springs N N' located in suitable barrels O O' and taking about a rod P, plungers p p' working in the barrels between the head p^2 and nuts p^3 on the rod.

A hold-down-bar Q is riveted to the web of 110
 60 the reinforce-rail M. This bar may consist of a piece of metal of substantially the width of the web of the rail and be bent back upon itself at its outer end, its inner ends being spread, so as to form feet q q', through which 115
 65 the bar is bolted to the rails. A hood R is secured to a track-plate with the upper inner face of the hood making contact with the

upper edge of the bar for preventing upward movement or tilting of the movable wing-rail when the wheels pass over it along the main rail or when pressed sidewardly by the wheels passing over the siding. The hold-down-bar and spring are preferably adjacent to each other at the free end of the movable wing-rail, so that the springs may exert their pressure directly against the movement of the rail for insuring a positive direct resistance of the shifting of the rail and at the same time applying the hold-down-bar at the point of greatest tendency of the movable wing-rail 120
 70 to tilt, the pivotal point of the movable wing-rail being at its other end in rear of the points of the main and siding rails.

Having thus fully described our invention, what we claim as new, and desire to secure by 85 Letters Patent, is—

1. In combination, with the main and siding point-rails, main and siding rails formed as continuations of the same and forming a gap between said points and the continuation 90 of the main rail, of a movable wing-rail swinging from a point in rear of the points of the main and siding rails and having a portion bent and extended longitudinally of the main rail when in normal position and taking into 95 said gap.

2. In combination, with the main and siding point-rails, main and siding rails formed as continuations of the same and forming a gap between said points and the continuation 100 of the main rail, of a movable wing-rail having a portion extending rearwardly of said points at an angle to said siding point-rail and hinged in rear of said points so as to swing from said hinged portion, said movable wing-rail having a further portion bent and extending longitudinally of the main rail when in normal position and taking into said gap.

3. In combination, with the main and siding point-rails, main and siding rails formed 110 as continuations of the same and forming a gap between the said points and the continuation of the main rail, of a movable wing-rail pivoted adjacent to one end in rear of the points of the main and siding rails and having 115 a portion bent longitudinally of the main rail when in normal position and taking into said gap, with a spring and a hold-down device acting upon the movable wing-rail toward its other end.

4. In combination, with the stationary main and siding rails, the main rail having a point with diagonal face, and a continuation of the main rail for forming a gap between the point and continuation, of a movable wing-rail pivoted at the side of the main and siding rails in rear of the point with a diagonal portion thereof normally taking against the diagonal face of the point, and a straight portion of the movable wing-rail normally 120 parallel with the main rail filling said gap, and a spring and hold-down device applied to the movable wing-rail at said gap.

5. In combination, a movable wing-rail piv-

oted to one end with a combined reinforce and riser rail secured to its other end.

6. In combination, with the main rail and continuation thereof for forming a gap therebetween, of a movable wing-rail pivoted on an upright pivot-pin and having its free end taking into the gap adjacent to the end of said continuation, and a combined reinforce and riser rail secured to the free end of the movable wing-rail spanning said adjacent ends.

7. In combination with a main rail and continuation therefor forming a gap therebetween, of a movable wing-rail pivoted toward its outer end and having its free end taking into the gap for having the ends of the movable wing-rail and continuation of the main rail adjacent to each other, and a combined reinforce and riser rail secured to the other end of the movable wing-rail and spanning said ends.

8. In a spring rail-frog, the combination with the main and siding points and a con-

tinuation of the main rail for forming a gap between said points and continuation, of a movable wing-rail having an upright pivot-pin outside the vertical planes and to rear of said points, a free end for said movable wing-rail parallel with the main rail taking into said gap, and a combined reinforce and riser rail secured to said free end and movable toward and from said continuation in an arc described from the pivot in rear of the points and spanning adjacent ends of said parallel portion of the movable wing-rail and said continuation of the main rail.

In witness whereof we have signed our names hereto in the presence of two subscribing witnesses.
